(57) **CLAIM**

The ornamental design for an LED side mount, as shown and described.

DESCRIPTION

FIG. 1 is a front view of a LED side mount showing my new design;

FIG. 2 is a right side view thereof;

FIG. 3 is a left side sectional thereof;

FIG. 4 is an oblique view thereof; and,

FIG. 5 is a back side view thereof.

In the drawings, the broken lines in FIGS. 1, 4 and 5 depict a star and form no part of the claimed design.
